CLAIM

The ornamental design for a combined electric vehicle charging station with status indicator lights, as shown and described.

DESCRIPTION

The file of this patent contains at least one drawing/photograph executed in color. Copies of this patent with colored drawing(s)/photograph(s) will be provided by the Office upon request and payment of the necessary fee.

FIG. 1 is a front view of a combined electric vehicle charging station with status indicator lights showing the new design with its status indicator lights in a first illumination configuration;

FIG. 2 is a front, left perspective view of the invention illustrated in FIG. 1;

FIG. 3 is a left view of the invention illustrated in FIG. 1; FIG. 4 is a right view of the invention illustrated in FIG. 1; FIG. 5 is a bottom view of the invention illustrated in FIG. 1;

FIG. 6 is a top view of the invention illustrated in FIG. 1; FIG. 7 is a rear view of the invention illustrated in FIG. 1; FIG. 8 is a front view of a combined electric vehicle charging station with status indicator lights showing the new design with its status indicator lights in a second illumination configuration;

FIG. 9 is a front, left perspective view of the invention illustrated in FIG. 8;

FIG. 10 is a left view of the invention illustrated in FIG. 8; FIG. 11 is a right view of the invention illustrated in FIG. 8; FIG. 12 is a bottom view of the invention illustrated in FIG. 8;

FIG. 13 is a top view of the invention illustrated in FIG. 8; FIG. 14 is a rear view of the invention illustrated in FIG. 8; FIG. 15 is a front view of a combined electric vehicle charging station with status indicator lights showing the new design with its status indicator lights in a first illumination configuration in a first sequence of illumination configurations;

FIG. 16 is a front, left perspective view of the invention illustrated in FIG. 15;

FIG. 17 is a left view of the invention illustrated in FIG. 15; FIG. 18 is a right view of the invention illustrated in FIG. 15; FIG. 19 is a bottom view of the invention illustrated in FIG. 15;

FIG. 20 is a top view of the invention illustrated in FIG. 15; FIG. 21 is a rear view of the invention illustrated in FIG. 15; FIG. 22 is a front, left perspective view of a combined electric vehicle charging station with status indicator lights showing the new design with its status indicator lights in a second illumination configuration in the first sequence of illumination configurations;

FIG. 23 is a front view of the invention illustrated in FIG. 22;

FIG. 24 is a left view of the invention illustrated in FIG. 22; FIG. 25 is a right view of the invention illustrated in FIG. 22, with a bottom view thereof being the same as FIG. 19, a top view thereof being the same as FIG. 20, and a rear view thereof being the same as FIG. 21;

FIG. 26 is a front, left perspective view of a combined electric vehicle charging station with status indicator lights showing the new design with its status indicator lights in a third illumination configuration in the first sequence of illumination configurations;

FIG. 27 is a front, left perspective view of the invention illustrated in FIG. 26;

FIG. 28 is a left view of the invention illustrated in FIG. 26; FIG. 29 is a right view of the invention illustrated in FIG. 26, with a bottom view thereof being the same as FIG. 19, a top view thereof being the same as FIG. 20, and a rear view thereof being the same as FIG. 21;

FIG. 30 is a front, left perspective view of a combined electric vehicle charging station with status indicator lights showing the new design with its status indicator lights in a fourth illumination configuration in the first sequence of illumination configurations;

FIG. 31 is a front view of the invention illustrated in FIG. 30; FIG. 32 is a left view of the invention illustrated in FIG. 30; FIG. 33 is a right view of the invention illustrated in FIG. 30, with a bottom view thereof being the same as FIG. 19, a top view thereof being the same as FIG. 20, and a rear view thereof being the same as FIG. 21;

FIG. 34 is a front, left perspective view of a combined electric vehicle charging station with status indicator lights showing the new design with its status indicator lights in a fifth illumination configuration in the first sequence of illumination configurations;

FIG. 35 is a front view of the invention illustrated in FIG. 34; FIG. 36 is a left view of the invention illustrated in FIG. 34; FIG. 37 is a right view of the invention illustrated in FIG. 34, with a bottom view thereof being the same as FIG. 19, a top view thereof being the same as FIG. 20, and a rear view thereof being the same as FIG. 21;

FIG. 38 is a front, left perspective view of a combined electric vehicle charging station with status indicator lights showing the new design with its status indicator lights in a sixth illumination configuration in the first sequence of illumination configurations;

FIG. 39 is a front view of the invention illustrated in FIG. 38; FIG. 40 is a left view of the invention illustrated in FIG. 38; FIG. 41 is a right view of the invention illustrated in FIG. 38, with a bottom view thereof being the same as FIG. 19, a top view thereof being the same as FIG. 20, and a rear view thereof being the same as FIG. 21;

FIG. 42 is a front, left perspective view of a combined electric vehicle charging station with status indicator lights showing the new design with its status indicator lights in a seventh illumination configuration in the first sequence of illumination configurations;

FIG. 43 is a front view of the invention illustrated in FIG. 42; FIG. 44 is a left view of the invention illustrated in FIG. 42; FIG. 45 is a right view of the invention illustrated in FIG. 42, with a bottom view thereof being the same as FIG. 19, a top view thereof being the same as FIG. 20, and a rear view thereof being the same as FIG. 21;

FIG. 46 is a front, left perspective view of a combined electric vehicle charging station with status indicator lights

FIG. 98 is a left view of the invention illustrated in FIG. 96; FIG. 99 is a right view of the invention illustrated in FIG. 96, with a bottom view thereof being the same as FIG. 89, a top view thereof being the same as FIG. 90, and a rear view thereof being the same as FIG. 91;

FIG. 100 is a front, left perspective view of a combined electric vehicle charging station with status indicator lights showing the new design with its status indicator lights in a fourth illumination configuration in the third sequence of illumination configurations;

FIG. 101 is a front view of the invention illustrated in FIG. 100;

FIG. 102 is a left view of the invention illustrated in FIG. 100;

FIG. 103 is a right view of the invention illustrated in FIG. 100, with a bottom view thereof being the same as FIG. 89, a top view thereof being the same as FIG. 90, and a rear view thereof being the same as FIG. 91;

FIG. 104 is a front, left perspective view of a combined electric vehicle charging station with status indicator lights showing the new design with its status indicator lights in a fifth illumination configuration in the third sequence of illumination configurations;

FIG. 105 is a front view of the invention illustrated in FIG. 104;

FIG. 106 is a left view of the invention illustrated in FIG. 104;

FIG. 107 is a right view of the invention illustrated in FIG. 104, with a bottom view thereof being the same as FIG. 89, a top view thereof being the same as FIG. 90, and a rear view thereof being the same as FIG. 91;

FIG. 108 is a front, left perspective view of a combined electric vehicle charging station with status indicator lights showing the new design with its status indicator lights in a sixth illumination configuration in the third sequence of illumination configurations;

FIG. 109 is a front view of the invention illustrated in FIG. 108;

FIG. 110 is a left view of the invention illustrated in FIG. 108;

FIG. 111 is a right view of the invention illustrated in FIG. 108, with a bottom view thereof being the same as FIG. 89, a top view thereof being the same as FIG. 90, and a rear view thereof being the same as FIG. 91;

FIG. 112 is a front, left perspective view of a combined electric vehicle charging station with status indicator lights showing the new design with its status indicator lights in a seventh illumination configuration in the third sequence of illumination configurations;

FIG. 113 is a front view of the invention illustrated in FIG. 112;

FIG. 114 is a left view of the invention illustrated in FIG. 112;

FIG. 115 is a right view of the invention illustrated in FIG. 112, with a bottom view thereof being the same as FIG. 89, a top view thereof being the same as FIG. 90, and a rear view thereof being the same as FIG. 91;

FIG. 116 is a front, left perspective view of a combined electric vehicle charging station with status indicator lights showing the new design with its status indicator lights in an eighth illumination configuration in the third sequence of illumination configurations;

FIG. 117 is a front view of the invention illustrated in FIG. 116;

FIG. 118 is a left view of the invention illustrated in FIG. 116;

FIG. 119 is a right view of the invention illustrated in FIG. 116, with a bottom view thereof being the same as FIG. 89, a top view thereof being the same as FIG. 90, and a rear view thereof being the same as FIG. 91;

FIG. 120 is a front view of a combined electric vehicle charging station with status indicator lights showing the new design with its status indicator lights in a third illumination configuration;

FIG. 121 is a front, left perspective view of the invention illustrated in FIG. 121;

FIG. 122 is a left view of the invention illustrated in FIG. 121;

FIG. 123 is a right view of the invention illustrated in FIG. 121;

FIG. 124 is a bottom view of the invention illustrated in FIG. 121;

FIG. 125 is a top view of the invention illustrated in FIG. 121;

FIG. 126 is a rear view of the invention illustrated in FIG. 121;

FIG. 127 is a front view of a combined electric vehicle charging station with status indicator lights showing the new design with its status indicator lights in a fourth illumination configuration;

FIG. 128 is a front, left perspective view of the invention illustrated in FIG. 127;

FIG. 129 is a left view of the invention illustrated in FIG. 127;

FIG. 130 is a right view of the invention illustrated in FIG. 127;

FIG. 131 is a bottom view of the invention illustrated in FIG. 127;

FIG. 132 is a top view of the invention illustrated in FIG. 127; and,

FIG. 133 is a rear view of the invention illustrated in FIG. 127.

A characteristic feature of the design resides in the colors of the light panels, when illuminated, of the combined electric vehicle charging station with status indicator lights, which colors include the color green and the color red.

The appearance of the light panels of the combined electric vehicle charging station with status indicator lights transitions sequentially between the first illumination configuration, illustrated in FIGS. 15-21, through the eighth illumination configuration, illustrated in FIGS. 46-49, in the first sequence of illumination configurations; between the first illumination configuration, illustrated in FIGS. 50-56, through the eighth illumination configuration, illustrated in FIGS. 81-84, in the second sequence of illumination configurations; and between the first illumination configuration, illustrated in FIGS. 85-91, through the eighth illumination configuration, illustrated in FIGS. 116-119, in the third sequence of illumination configurations. The process or period in which the appearance of the combined electric vehicle charging station with status indicator lights transitions from one configuration to another of the respective sequence forms no part of the claimed design.

The parallel diagonal shade lines in the pill-shaped regions in the drawings indicate transparency or translucency. The relatively long broken lines extending outwardly from the transparent or translucent pill-shaped regions indicate that those regions are illuminated.

The broken lines in the drawings depict portions of the combined electric vehicle charging station with status indicator lights that form no part of the claimed design.
